UNITED STATES PATENT OFFICE.

THOMAS HINDS, OF WINNIPEG, MANITOBA, CANADA.

PIPE-WRENCH.

Specification of Letters Patent.

Patented Aug. 4, 1914.

1,105,782.

Application filed July 9, 1913. Serial No. 778,186.

To all whom it may concern:

Be it known that I, THOMAS HINDS, of the city of Winnipeg, in the Province of Manitoba, Canada, have invented certain new and useful Improvements in Pipe-Wrenches, of which the following is the specification.

The invention relates to an improvement in pipe wrenches and the object of the invention is to provide primarily a plumber's wrench which when applied will fit and grip the various sizes of pipes customarily found in plumbing installations the parts being especially designed so that the gripped pipe is not materially marred or injured.

5 A further and important object of the invention is to provide a wrench which can be readily released from the pipe the parts being designed so that they are entirely automatic in this regard.

10 A still further object of the invention is to provide in this type of wrench one having a renewable gripping section in the stationary jaw.

With the above objects in view the invention consists essentially in a stationary jaw 25 extended into a handle and provided with a recess, a renewable gripping section carried by the jaw and a rotary jaw partially contained within the recess and designed to 30 coöperate with the stationary jaw to grip the pipe, the parts being arranged and constructed as hereinafter more particularly described and later pointed out in the appended claim.

35 Figure 1 represents a face view of the wrench with a portion of the handle broken away. Fig. 2 is a side view of the wrench. Fig. 3 represents a vertical sectional view through the wrench. Fig. 4 is a diagrammatic view showing the manner in which the wrench is constructed.

In the drawing like characters of reference indicate corresponding parts in each figure.

45 1 represents a stationary or permanent jaw which extends into a handle 2 of any suitable design. The jaw is recessed at 3 to receive a rotary jaw 4, the said jaw being mounted on a cross pivot pin 5 carried by 50 the side walls of the recess.

60 6 represents a removable gripping section which section is let into the stationary jaw and is provided on the one side with a plurality of serrations forming teeth 7 and at 55 the opposite side with an extending lug 8, the lug fitting into a suitable notch 9 formed

in the jaw in which notch it is held by a removable pin 10. The rotary jaw has pieces of varying size cut out from the margin thereof leaving reentrant curves 11, 12, 60 13 and 14.

The above completes the description of the parts but I wish now to draw particular attention to the manner in which these parts are constructed and arranged.

65 In constructing the present wrench I have assumed that for all practical purposes it is only necessary to have the wrench grip four sizes of pipes, that is one-half inch, three-quarters inch, one inch and one inch and a quarter as these sizes of pipes are practically all that are found in the average plumbing installation. Further I have concluded that it is impracticable to try and make a serviceable wrench which will grip 75 a large number of varying size pipes. Further I have found that the average plumber will use a small or light wrench on small pipes and a heavy wrench on larger pipes 80 and would not take a large or heavy wrench with adjustments for all pipes where only a small pipe was to be gripped. For the above reasons I find that a wrench with four 85 adjustments is sufficient for all practical purposes.

85 In designing my wrench reference being now had particularly to Fig. 4 I first lay off a base line such as that *a*—*b* and then on this base line describe four circles *c*, *d*, *e* and *f* these circles having their centers located on the base line as at *c'*, *d'*, *e'* and *f'* respectively. The circles are arranged so that their circumferences all touch at one point *g* as indicated. I then sweep an arc 90 of a circle *h*, this arc passing through the point *g* and having its center located at *h'* on the base line. The radius of this circle is chosen greater than the radius of the circle *f*. The circles *c*, *d*, *e* and *f* so plotted correspond to the actual sizes of the various 100 pipes which the completed wrench is designed to grip and the point *g* represents the contact point of the various pipes with the stationary jaw, this point remaining constant for all pipes. The teeth 7 of the 105 gripping section are designed to fall on the arc *h* as indicated in dotted outline in Fig. 4. I next choose a point *l* the particular limitation of which is that it must be above the base line. With this point as center I 110 describe a circle *p* which cuts or intersects the various circles *c*, *d*, *e* and *f*. The por-

tions of these latter circles contained within the circle p are rotated to various points in the circle p and are drawn in full lines in said Fig. 4, as reëntrant curves r , s , and t , these curves actually being the cut away portions of the rotary jaw as shown in the remaining figures. It will be seen that the points d' , e' , and f' have been rotated to the positions d^2 , e^2 and f^2 and that these latter points are the centers of the reëntrant curves r , s and t . Accordingly when the parts so designed are combined in the completed wrench, the pin 5 actually being the center 1, the point g actually being the center gripping point of the teeth 7 and the reëntrant curves r , s , t and x the cut away portions 11, 12, 13 and 14 of the rotary jaw, it will be seen that all the various sizes of pipes will be gripped by the same point on the stationary jaw which gripping point will be at all times below the pivot pin 5, or in other words contained within the base line $a-b$. Further it will be seen that the various centers of the pipes gripped can never be above the straight line O (see Fig. 4) joining the contact point of the pipe with the stationary jaw and the center of the pin 5. By virtue of the construction the wrench in use can never lock on the pipe. In other words immediately the handle is withdrawn the rotary jaw will turn freely and release the wrench from the pipe. This is a very important feature and for this reason I have seen fit to show diagrammatically and ex-

plain fully the actual design. In the drawing a small pipe A has been shown in the gripped position.

What I claim as my invention is:

A pipe wrench for gripping pipes of fixed different radii comprising a handle presenting a permanent gripping jaw having a constant gripping point for the various sizes of pipes, said jaw presenting teeth contained within the arc of a circle the radius of which is greater than the radius of the largest pipe to be gripped and a pivotally mounted rotary jaw carried by the handle having portions of the margin thereof cut away to present suitably spaced reëntrant curves, the radii of said curves corresponding to the radii of the pipes to be gripped, said pivot point being contained in a horizontal plane located above the center point of the arc containing the teeth of the stationary jaw and the reëntrant curves being designed so that in the gripped positions of the various pipes the centers of the reëntrant curves lie on a straight line connecting the fixed gripping point of the fixed jaw with the center point of the arc, as and for the purpose specified.

Signed at Winnipeg, this 26 day of May, 1913.

THOMAS HINDS.
